THERMOSTATIC UNIT

John E. Woods, Brookline, Mass., assignor to
 Clifford Manufacturing Co., Boston, Mass., a
 corporation of Delaware

Application February 10, 1940, Serial No. 318,268

2 Claims. (Cl. 200—140)

The present invention relates to a thermostatic unit particularly designed for insertion in an open cooking vessel where it is desired to maintain water or the like under atmospheric pressure at the boiling point, or in close relation thereto. Such a unit, by cutting down on the input of heat when the boiling point is reached, will maintain the boiling water at the most economical temperature for cooking without an excess of heat which merely serves to boil the water away at a faster rate without accomplishing any useful cooking function.

I have found in connection with such a unit that in order to automatically compensate for changes in the boiling point caused by differences in atmospheric pressure which may be created by changes in the barometer or by changes in the altitude, it is necessary to provide a type of control which shall automatically fluctuate as the atmospheric pressure changes, and thus maintain the boiling point automatically at whatever temperature may be required at any given atmospheric pressure.

With this in view, I have designed a simple, compact, unitary structure which may be immersed directly in the cooking water without injury either to the unit or to the food in process of cooking, and which when properly connected with a source of heat such as an electric coil, will control the coil through an appropriate relay and switching mechanism.

The drawing illustrates the preferred embodiment of the invention in the form of a sectional elevation of the unit.

Referring particularly to the drawing, the unit as a whole is housed in a cylindrical casing 10 threaded at opposite ends at 12 and 14. On the inner end of the casing as threaded at 12 is attached a sleeve 16, on which is mounted a generally radial flange 18 carrying a cap 20 which forms the outer wall of a thermostatic chamber, the movable wall of which is constituted by a diaphragm 22 sealed to the interior of the cap through a solder bond 24. The central portion of the diaphragm carries a threaded member 26 upon which is mounted a stem 28 guided loosely at its outer end in an insulating block 30 received within the casing. The insulating block has an extended arm 32 carrying a switch contact 34. A second and movable arm 36 carrying a complementary contact 38 is pivoted at 40 and engaged by the free end of the stem 28 to be actuated by movement of the stem under the influence of the diaphragm. A leaf spring 42

connected to the movable arm at 44 and bearing against the inner wall of the casing serves to maintain the arm in engagement with the stem and impose a spring load upon outward movement of the diaphragm. The inner wall of the casing about the contacts and electrical connections may be lined with a fibre tube 46, and each contact is provided with a terminal connection 48 and 50, from which extend leads 52 and 54 through a head 56 threaded upon the opposite end of the tube. From this point the leads may be connected through appropriate terminals with a relay and switch for controlling the heat input.

It will be noted that the parts may be readily retained in assembled relationship by providing a spring 60 received within the casing and interposed between the block 30 which has a shoulder 62 held against a complementary shoulder within the casing, and a seat 64 connected to the sleeve 16 by a soldered joint 66. When the sleeve is threaded upon the end of the casing the spring forces the block into firm contact with the shoulder and maintains it in this relationship.

I propose to fill the thermostatic chamber in 25 the head in such a fashion that it normally operates on the vacuum side, employing the natural curvature of the diaphragm to open the contacts. With this construction, so long as the vacuum exists within the chamber, the contacts 30 will remain closed, but upon elevation of temperature or failure of the diaphragm which causes the vacuum to fail, the contacts automatically open.

I accomplish this result by subjecting the 35 chamber through the opening 10 to a vacuum, and thereafter inserting therein an appropriate amount of liquid having a somewhat higher boiling point than water in order that the vapor pressure of the contained liquid shall overcome the vacuum and permit the diaphragm to open the circuit at the boiling point of water at whatever atmospheric pressure may exist, since the outer surface of the diaphragm 22 is exposed to atmospheric pressure. This can be accomplished by employing xylene or toluene or mixtures of the two. In adjusting the unit for proper temperature conditions, the lower end of the unit containing the thermostatic chamber may be immersed in boiling water, and the sleeve 16 is then adjusted on the threaded connection until the contacts are caused to break at the desired temperature at which the unit operates. Thereafter the head and sleeve may be soldered as indicated at 72 to retain the adjustment.

What is claimed is:

1. An immersion unit for controlling heat input, which comprises a generally tubular casing, a support of insulating material fixedly mounted within the casing and having a circuit contact mounted thereon, a pivoted arm mounted adjacent thereto and carrying a complementary contact, a head connected to the casing and having a thermostatic chamber therein, a diaphragm constituting the movable wall of the chamber, an operating rod connected with the movable wall and contacting the pivoted arm, thermostatic fluid within the chamber vaporizable at the temperature range, a spring interposed between the insulating material and the head, and means for adjusting the head longitudinally of the casing to predetermine the temperature of operation.

2. An immersion unit for controlling heat input, which comprises a thermostatic chamber having an outer wall and a movable diaphragm forming the inner wall, a tubular mounting connected with the outer wall and constructed to apply atmospheric pressure to the diaphragm when the thermostatic chamber is immersed, a medium within the chamber vaporizable at the operating range to operate the diaphragm at approximately the boiling point of water at any atmospheric pressure, circuit contacts enclosed within the tubular mounting, and connections between the diaphragm and the circuit contacts for opening the contacts upon expansive movement of the diaphragm.

JOHN E. WOODS.
